Primary Examiner — Calvin E Vansant*Assistant Examiner* — Mark T. Philipp(74) *Attorney, Agent, or Firm* — Bayramoglu Law Offices LLC(57) **CLAIM**

The ornamental design for a bilge submersible pump, as shown and described.

DESCRIPTION

FIG. 1 is a perspective view of a bilge submersible pump showing my new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken lines depict portions of the bilge submersible pump in which the design is embodied that form no part of the claimed design.

1 Claim, 7 Drawing Sheets(56)
